CLAIM

The ornamental design for a microscope, as shown and described.

DESCRIPTION

The patent or application file contains at least one drawing executed in color. Copies of this patent or patent application publication with color drawing(s) will be provided by the Office upon request and payment of the necessary fee.

FIG. 1.1 is a front view of a microscope showing our new design;

FIG. 1.2 is a rear view thereof;

FIG. 1.3 is a left side view thereof;

FIG. 1.4 is a right side view thereof;

FIG. 1.5 is a top view thereof;

FIG. 1.6 is a bottom view thereof; and

FIG. 1.7 is a front, left, top perspective view thereof.

In the drawings, broken lines and lightened shading therein show portions of the microscope that form no part of the claimed design.
